UNITED STATES PATENT OFFICE

AMUNDUR FRØISLAND, OF OSLO, NORWAY

PUMP FOR THE CONVEYANCE OF THICK FLUID PULPS

Application filed April 26, 1930, Serial No. 447,494, and in Norway May 1, 1929.

The present invention relates to a pump for the conveyance of thick-fluid pulps, particularly concentrated wood pulp and the like, the novelty of the invention consisting in 5 rotatably mounting within a suitable casing one or more knives of such shape that while cutting through the pulp there is set up at one side, by reason of the vacuum created during the rotation of the knives a suction 10 of the pulp into the pump casing and at the other side a static pressure thereon, whereby a suitable and economically advantageous conveyance of the pulp is secured.

The invention is illustrated by way of example in the annexed drawing, wherein:

Fig. 1 shows a cross section of a pump in accordance with the invention.

Fig. 2 is a side view of the pump wheel on the line II—II of Fig. 1.

In the drawing 1 denotes the pump casing with pulp inlet 2 and pulp outlet 3. The pump wheel which is keyed to the end of the shaft 4 consists of a circular plate 6 connected to the hub 5. The plate carries two knives 7, 8, of such shape that the ratio of increase of their radial depth to the angle subtended at the centre of rotation is substantially constant. In order to facilitate cutting through the pulp, the front edges of the knives are pointed and in order to stiffen the knives and facilitate guiding of the pulp the knives are also provided on the inlet side with lateral flanges extending from the front edge of the knife and the exterior edge of which joins the knife at a suitable angular distance therefrom. 9 denotes a stationary plate which by means of the arm 10 is carried from the wall in the pump casing inlet. The purpose of this blade is to prevent the pulp following the knives during their rotation.

The pump operates in the following manner:

During their rotation the knives will cut through the pulp with their edges. The spiral shape of the knives will have the effect that during their rotation a vacuum will be developed on their interior side which will secure a supply of pulp to the interior of the pump wheel, whereas on the exterior the 50 knives will exert a static conveying pressure

upon the pulp, so that the latter will be forced substantially uninterruptedly up through the outlet 3. The inlet 2 is of such dimensions that even a thick-fluid pulp will not be liable to choke up the passages, the plate 9 preventing the pulp from rotating with the knives.

I claim:

1. A pump for thick-fluid pulps, characterized by a pump wheel having knife-shaped blades perpendicularly supported by a radial disc provided with a hub and mounted on a shaft in such manner that the central portion of the pump wheel is open, the pulp obtaining free access thereto notwithstanding its consistency, said blades being of such shape that during rotation they create on the one side a vacuum inducing a flow of the pulp supply, whereas on the other side they set up a static pressure action upon the pulp cut off by the blade knives, whereby the pulp is conveyed outwardly in direct proportion to the angular motion of the wheel.

2. A pump for thick-fluid pulps, characterized by a pump wheel having a knife-shaped blade or blades supported by a radial disc provided with a hub and mounted on a shaft in such manner that the central portion of the pump wheel is open, the pulp obtaining free access thereto notwithstanding its consistency said blade or blades being of such shape that during rotation they create on the one side a vacuum inducing a flow of the pulp supply, whereas on the other side they set up a static pressure action upon the pulp cut off by the knives, whereby the pulp is conveyed outwardly in direct proportion to the angular motion of the wheel, the knife edges of the wheel at the side opposite the radial supporting disc having lateral reinforcing flanges, the height of which decreases uniformly from the front edge of the blade knife inwardly to the peripheral surface of the knife.

3. A pump for thick-fluid pulps, characterized by a pump wheel having a knife-shaped blade of semi-circular curved shape eccentrically mounted thereon so that during rotation creates on the one side a vacuum inducing a flow of the pulp supply, whereas

on the other side it sets up a static pressure action upon the pulp cut off by the knives, whereby the pulp is conveyed outwardly in direct proportion to the angular motion of the wheel, and a stationary baffle being arranged for preventing the pulp from rotating with the blade wheel, said blade on the wheel being disposed perpendicular to the face of the pump wheel.

10 4. A pump for thick-fluid pulps comprising a casing having an inlet and outlet, and a pump wheel within the casing and rotatable therein, said wheel having a plurality of curved blades eccentrically disposed about the center of the wheel, and perpendicular to the face of the wheel, the cutting edge of one blade being in vertical alignment with the cutting edge of the other blade, whereby to provide a space therebetween for the injection and expulsion of the pulp on rotary action of the blades.

5. In a conveying pump for thick fluid pulp, a pump wheel having a radial disc, a plurality of semicircular knife blades projecting perpendicularly from the disc and eccentrically mounted thereon so that the ratio of increase of their radial depth to the angle subtended at the center of rotation of the wheel is substantially constant whereby during rotation the pulp is conveyed outwardly of the pump in direct proportion to the angular motion of the wheel, and a stationary baffle plate mounted in the pump extending into the wheel beneath the knife edge of the blades for preventing pulp from following the blades during their rotation.

In testimony whereof I have affixed my signature.

AMUNDUR FRØISLAND.
